UNITED STATES PATENT OFFICE.

WILLIAM SUMNER, OF LIVERPOOL, ENGLAND.

CURRENT-REGULATING DEVICE OR RESISTANCE APPLICABLE FOR ELECTRIC LIGHTING OR HEATING.

1,037,683.

Specification of Letters Patent. Patented Sept. 3, 1912.

Application filed January 5, 1912. Serial No. 669,667.

To all whom it may concern:

Be it known that I, WILLIAM SUMNER, a subject of the King of Great Britain, residing at 31 Moira street, Liverpool, England, have invented certain new and useful Improvements in Current-Regulating Devices or Resistances Applicable for Electric Lighting or Heating, of which the following is a specification.

10 This invention relates to improvements in electric current regulating devices or resistances and is especially applicable for use in connection with incandescent lamps whereby the current supplied to the lamp 15 may be regulated as required to any minimum and the luminosity of the lamp filament varied accordingly, or the device may be used as an electric heater.

Resistance devices or "dimmers" for electric lamps are known in which the medium of which the resistance is composed consists of a loose mixture of powdered mica, sand and graphite, the resistability of the medium being varied according to the degree of compression applied thereto. Such a resistance is however unsatisfactory inasmuch as there is not sufficient elasticity in the composition to cause it to restore itself to its normal condition when released from compression, and further, the several constituents of the mixture, even if intimately intermixed in the first instance, are apt in course of time owing to vibration or the continued operation of compressing and releasing, to separate themselves and thus destroy the homogeneous character or evenness of the mixture, thereby causing the effectiveness of the resistance to be impaired. Resistances of this class are also known comprising a mixture of asbestos and carbon in the form of a pad adapted to be compressed for the purpose of varying the resistance. Such a preparation is, however, unsatisfactory owing to the fact that the small percentage of carbon which is requisite to effect the desired control of the comparatively small current passing through an incandescent lamp, cannot, by commercial methods, be evenly incorporated with the asbestos. Unless the carbon is very evenly distributed throughout the mixture composing the resistance it is impossible to obtain the nicety of or minute control of the current necessary to effect say, a gradual dimming of the luminosity of an electric

incandescent lamp as when pressure is applied to the resistance a possible localization of the path of the current through the resistance may be set up, in which case a faint glow of the filament of the lamp would be 60 impossible so long as any pressure was maintained and on the removal of the pressure arcing may result.

In the making of electric resistances from a series of sheets of fibrous material it has 65 been proposed to coat the fibrous material on each side with coal tar, the sheets being subsequently heated to carbonize the fiber, but in this my invention the resistances after impregnation with the mixture hereinafter described are heated to increase the 70 resiliency of the said resistances.

The present invention is directed to obtaining a resistance pad or the like which shall be characterized by an even and comparatively rare distribution of the carbon particles throughout a fibrous body or support, and which shall have a considerable elasticity. To effect this, I make a mixture of finely ground plumbago or analogous preparation of carbon reduced to the condition of an impalpable powder, and finely powdered chalk or the like insulating medium in the proportion of about 25% of plumbago to 75% of chalk by weight. 80 This mixture is then intimately incorporated with the fibrous material, preferably asbestos flax, in any suitable manner, say by revolving them together in a receptacle, or treating them in a mixer until the asbestos is thoroughly impregnated with the mixture. Any excess of the plumbago and chalk is then shaken out. Such a method of treating the asbestos with a mixture of plumbago 85 and chalk insures a very even and comparatively rare distribution of the particles of plumbago throughout the asbestos to be effected in a manner practicable on a commercial scale. The asbestos so prepared is then spun into yarn and coiled, wound or otherwise made up into pads or the like which, in a suitable construction, may be mounted within an asbestos, fiber or other fireproof shell or casing closed at one end by a contact plate or the like connected to one end 90 of the electrical conductor of the circuit to be controlled.

The accompanying drawings show by way of example several methods of preparing a resistance pad from coiled or wound 100

yarn and of mounting it within a box or casing.

Figures 1 and 2 are an elevation and plan respectively of a pad produced in accordance with this invention by simply coiling up an impregnated asbestos yarn or cord. Figs. 3 and 4 show the successive stages of a modified arrangement in which the pad is prepared by transversely winding the spun 10 yarn upon a base plate. Figs. 5 and 6 are an elevation and plan respectively of a further modification in the construction of the pad, the latter being here made from a coiled strand formed by winding the asbestos yarn upon a wire core. Fig. 7 is a longitudinal section showing a single pad mounted in a box or casing and having a controlling screw to form a regulating device suitable for an ordinary incandescent 20 lamp and Fig. 8 is a longitudinal section showing how several pads may be assembled to provide a resistance of large capacity.

In the form of regulator shown in Fig. 7 suitable for controlling an incandescent 25 lamp, the pad *a* is mounted within an asbestos or other fireproof insulating box or casing *b*. Arranged at each end of the pad *a* are metallic contact plates or disks *c* and *d* respectively capable of being connected up 30 to the leads or terminals *e*, *e* of the circuit to be controlled. The contact disk *c* has preferably a direct connection with the lead or terminal *e* while the connection between the contact disk *d* is preferably effected through 35 a spring *f* connected to the lead or terminal and adapted to be pressed against the outer side of the plate *d* by a regulating screw *g* or other compression device, by the operation of which the spring is pressed against 40 the plate *d* and the compression of the pad effected, the current passing through the said pad to the contact plate *c*.

The asbestos or fibrous material after being impregnated with the mixture of plumbago and chalk is spun into a yarn or cord *h* which is then wound to the required shape 45 of the pad or resistance. Such a method of forming the impregnated asbestos into a yarn and winding it into a pad achieves a very even distribution of the plumbago throughout the mass of the pad and gives 50 to the pad a very considerable elasticity, while the method also lends itself admirably to the production of pads in great quantities 55 and on a commercial scale by unskilled labor, each pad having the same degree of resistance. If desired, the impregnated yarn may be wound on a wire core *i*, Figs. 5 and 6, which is then subsequently coiled to 60 form a pad or the like, the core being left in or removed, or the spun yarn *h* may be wound transversely to form several layers around a metal or other disk or plate *k*, Figs. 3 and 4, a series of such pads being, if 65 desired, superimposed to form a composite

pad. The asbestos or other fibrous yarn may be impregnated with the plumbago preparation after it is in the form of a yarn, but it is much preferred to first impregnate the fibrous material and then spin it into the yarn or cord. The pads in whatever way prepared are supported by metallic plates or disks as above described.

A lamp connected to the regulating device represented in Fig. 7 receives the maximum amount of current when the resistance pad is compressed to the full extent by the operation of the screw *g*, but by rotating the said screw in the direction proper for relaxing the pressure on the pad, the resiliency 75 of the same effects its expansion, thus increasing the resistance and causing a diminution of the brightness of the light corresponding with the extent to which the pressure is relaxed.

The asbestos shell or casing *b* may be enclosed in a porcelain casing or otherwise, in the cover of which the regulating screw may be carried. To obtain the best results it is necessary that the pad should not be 90 completely released from compression even when the faintest glow is required on the lamp or the smallest current passing through the pad, and this result can only be obtained when the particles of carbon are so 95 equally distributed throughout the asbestos that no matter what the degree of compression on the pad its substance will maintain an even conductivity throughout at all stages though this conductivity as a whole 100 varies in accordance with the compression. Such homogeneity in the conductivity of the pad is brought about by the rare, but equal, distribution of the carbon particles owing to their being first mixed with the chalk or the 105 like preparatory to being incorporated with the asbestos, and also owing to this rare but equal distribution the current may be controlled to a minimum and practically 110 cut off, the pad still being under some compression.

The resiliency of the pad, which is an essential feature of its successful working, may be increased by heating the pad after 115 being prepared with the plumbago and chalk, to a white heat and then allowing it to cool. In the case of adapting the device for use with currents of large amperage, or for heating resistances, I may mount the pads *a* in a series one upon another, as 120 shown in Fig. 8, and alternated with metallic disks *d* between each pad.

A pad produced in the manner described may be made of very small dimensions, say, about five eighths of an inch diameter by 125 one eighth deep for the control of an ordinary incandescent lamp, thus lending itself to the construction of a very compact type of device.

Although the invention has been de- 130

scribed with some special reference to incan-
descent lamps it may be applied to the con-
trol of other forms of electric lighting or to
the control of electric currents generally and
5 the resistances may constitute independent
devices introduced into the circuit to be con-
trolled or they may be adapted to form
parts of switches or other current control-
ling devices.

10 Having now described my invention what
I claim as new and desire to secure by
Letters Patent is:—

The process of producing a resistance
medium which consists in impregnating

fibrous material with an intimate mixture 15
of carbon and finely divided insulating ma-
terial, spinning the impregnated fibrous ma-
terial into a yarn, coiling the yarn to form
a pad, heating the pad to a high tempera-
ture, and finally cooling the heated pad. 20

In testimony whereof I have hereunto set
my hand in presence of two subscribing wit-
nesses.

WILLIAM SUMNER.
